UNITED STATES PATENT OFFICE.

MARY DONALD, DECEASED, BY REGINALD A. J. COOK, ADMINISTRATOR, OF BROOKLYN,
NEW YORK, ASSIGNOR TO MARTHA R. COOK, OF BROOKLYN, NEW YORK.

METHOD OF MAKING VEILS.

1,180,705.

Specification of Letters Patent. Patented Apr. 25, 1916.

Application filed September 22, 1915. Serial No. 52,096.

To all whom it may concern:

Be it known that I, REGINALD A. J. COOK, a citizen of the United States of America, and a resident of Brooklyn borough of the city of New York, county of Kings, and State of New York, am the administrator of the estate of MARY DONALD, late a citizen of the United States, deceased, who invented a certain new and useful Method of Making Veils, of which the following is a specification, the same being a full, clear, and exact description of the invention, such as will enable others skilled in the art to which it appertains to make and use the same.

This invention relates to articles made of lawn or lace or other fabric or material adapted for ladies' use, and in particular to a piece of gauze, grenadine, lace, crape or other similar fabric used to cover the face and hair as a protection against the sun or wind, and adapted to be attached to the bonnet or hat, and also to the mode of constructing the same, and which embodies certain novel features of manufacture, and combination and arrangement of parts, of simple construction, neat in appearance, and efficient and serviceable in operation or use.

In order to enable the invention to be fully understood I shall proceed to explain the same by reference to the drawings, illustrative of one embodiment of the invention, which accompany and form a part of this specification, and in which—

Figure 1 represents an elevation of an ordinary veil before being made up according to the invention; Figs. 2, 3 and 4 are views in detail of different operations showing the manner in which the veil is constructed; and Fig. 5 is an elevation of the completed veil after the present invention has been embodied therein.

Like letters of reference indicate like parts in all the views.

This invention pertains to veils of the character of the one patented by Mary Donald on March 12, 1912, No. 1,020,083, and is an improvement in the method of making the same.

Referring particularly by reference characters or symbols to the drawings, A denotes the body of a veil, and A' the edge or hem, or lower portion, as used in practice, of the central part thereof, which edge is preferably made so as to be thicker than the rest of the said veil. The said thickened edge A'

preferably consists of a band sewed or otherwise attached to the body of the veil, at least the central part thereof and preferably extending along the whole edge of the veil.

At certain points along the longitudinal edge A' and at a substantial distance from the center, as at a⁵, the veil is fulled or shirred, or made in small puckers, plaits, folds or gathers, as for example, in the present instance, by making a bend or fold a at the edge of the veil, and another bend or fold a' ordinarily overlapping the former one. These folds or bends are preferably sewed, or otherwise attached together, whereby the gathers a² are formed in the central portion of the body of the veil adjacent to the said bends or folds. The two lateral ends or bordered edges of the part A' located at the central portion of the veil are constructed and arranged so as to meet or overlap, in practice, at the back of the neck, and may be, and preferably are, held together by attaching means of any desired character, as, for example, the fastenings a³, which may be snap buttons; or, if desired, hooks and eyes, or other securing means, may be used.

The veil, consisting of the central portion of the body thereof, and also of the end—or wing-like—portions of the said veil, preferably extending off at each side of said engaging edges at an angle from the central portion of the said body, may be tied, in use, around the hat, as described in the said patent.

It has been found in practice that a veil made according to the said patent and constructed as set forth above and as thus far described, has too much fullness in front of the face and will tend to hang down below the chin, thus presenting an untidy or baggy appearance, which is not only an annoyance to the wearer thereof but is unsightly as well. In order to remedy this defect and to improve the appearance of the veil when worn in the manner described, the band A' is ripped off, or otherwise detached from, that portion of the edge of the veil between the gathers or turned over corners, the said loosening of the band preferably extending almost to the said corners or folds, and the central portion of the body A of the veil is then pulled in a relatively outward direction, as shown at A⁵ in Fig. 4, to remove the excess of fullness, after which the said

band is again sewed on, or otherwise attached to, the veil, and finally, the projecting portion A⁵ of the veil is cut off, as illustrated in Fig. 5 showing the improved 5 completed veil, whereupon the veil, in use, will be found to have become shaped to the face, so as to rest snugly against and under the chin, and it will consequently present a neat and pleasing appearance when worn 10 over the face, as the body of the veil is narrower in width between the folded over points than elsewhere.

I wish it to be understood that I do not desire to be limited to the exact details of 15 construction shown and described herein, for various modifications will occur to a person skilled in the art.

What I claim as the invention is:—

20 The method of making and shaping a veil, comprising the following steps, namely; first, constructing the same with a thickened edge or border at at least the central portion of one longitudinal edge to provide reinforcing means; second, gathering the edge

at two points at a substantial distance from 25 the center to provide a fullness at the said gathers; third, suitably securing the said gathers in position; fourth, unloosening the reinforcing means from the veil intermediate 30 the gathers; fifth, pulling the central portion of the veil so as to project in a relatively outward direction between the said gathers to remove excess of fullness; sixth attaching the loosened portion of the reinforcing means to the veil; and finally, cutting 35 off the projecting part of the veil.

In testimony of the foregoing specification, I do hereby sign the same in the borough of Brooklyn of the city of New York, in the county of Kings and State of New 40 York, this 25th day of August, 1915.

REGINALD A. J. COOK,
*Administrator of the estate of Mary Donald,
deceased.*
